[57] **CLAIM**

The ornamental design for an insulated holder for beverage cans or the like, substantially as shown and described.

DESCRIPTION

FIG. 1 is a front elevational view of an insulated holder for beverage cans or the like showing our new design;

FIG. 2 is a rear elevational view thereof;

FIG. 3 is a side elevational view thereof as seen from

the right or left of FIG. 1;

FIG. 4 is a top plan view thereof;

FIG. 5 is a bottom plan view thereof;

FIG. 6 is a longitudinal section taken along line 6—6 of

FIG. 7, and

FIG. 7 is a top plan view thereof on an enlarged scale with the cap removed to show the three angularly spaced longitudinally extending ribs and the three spacing pips on the bottom cap.

FIG. 1.

FIG. 2.

FIG. 3.

FIG. 4.

FIG. 5.

FIG. 6.

FIG. 7.
